UNITED STATES PATENT OFFICE.

WILLIAM R. PARARO, OF BENHADEN, FLORIDA.

RAIL-TIE-SPACING DEVICE.

1,122,150.

Specification of Letters Patent.

Patented Dec. 22, 1914.

Application filed June 8, 1914. Serial No. 843,844.

To all whom it may concern:

Be it known that I, WILLIAM R. PARARO, a citizen of the United States, residing at Benhaden, in the county of Wakulla and 5 State of Florida, have invented certain new and useful Improvements in Rail-Tie-Spacing Devices, of which the following is a specification.

My invention relates to improvements in 10 devices for spacing rail ties and resides in the provision of novel means whereby ties may be spaced from each other into the desired position in an extremely reliable and expeditious manner.

15 Another important object of my invention is to provide a device that is to be positioned upon a rail and is to coöperate with a jack of the ordinary type so that the head of the jack may be placed against said 20 means and the base against the tie to be spaced and upon operation of the jack, the tie is spaced in the desired manner.

Another object of importance is to provide simple means of the character described that will, owing to its peculiar construction enable a great number of ties to be spaced in a comparatively short time and by few laborers, said device being simple as to construction and inexpensive to 30 manufacture.

The above and additional objects are accomplished by such means as are illustrated in the accompanying drawings, described in the following specification and then more 35 particularly pointed out as claimed.

With reference to the drawing, wherein I have illustrated the preferred embodiment of my invention as it is reduced to practice, and throughout the figure in which similar 40 reference numerals designate corresponding parts, the figure represents a perspective view showing my device in operative position.

Referring to the drawings by characters 45 of reference, the numeral 1 designates a rail mounted on ties 2 of the ordinary type and 3 a lifting jack of the ordinary construction usually found in railway tools.

My improved spacing device comprises an 50 approximately rectangular and preferably

metallic body 4 that is provided intermediate its ends with a transverse opening 5 formed in the under face of the body and designed to receive the ball of a rail as shown in the drawing. The upper end 55 faces of the body 4 are beveled as at 6 and provided centrally of their ends on the upper faces of the body is an upstanding flange 7 forming a handle portion and provided along its upper longitudinal edges 60 with projecting ribs 8 to enable gripping of the handle. If desired an opening may be formed in the handle portion 7.

In operation, my improved device is placed upon a rail so that a transverse central opening 5 receives the ball of the rail and the jack 3 is disposed in an angular plane with relation to the rail with its head in engagement with the projected portion of the body 4 with its face in engagement 65 with the tie to be spaced as clearly shown in the drawing. By proper manipulation of the jack 3 the tie that engages the face of the jack will be spaced relatively to the rail and other ties. The angular disposition of the jack relative to the rail and body 70 of the device provides for the gripping of the body on the head or ball of the rail and prevents slipping. 75

It will be readily seen with reference to 80 the foregoing description and accompanying drawings that in a comparatively short time a few men can space a large number of ties in a reliable manner.

In practice, I have found that the form 85 of my invention, illustrated in the drawings and referred to in the above description, as the preferred embodiment, is the most efficient and practical; yet realizing that the conditions concurrent with the 90 adoption of my device will necessarily vary, I desire to emphasize the fact that various minor changes in details of construction, proportion and arrangement of parts may be resorted to, when required, without sacrificing any of the advantages of my invention, as set forth. 95

What is claimed is:—

A rail tie spacing device comprising a rectangular body having a transverse open- 100

ing formed in its under face and centrally of its ends to receive the ball of a rail, said opening being approximately rectangular and of considerably greater width than that 5 of the ball of the rail, the ends of said body being beveled upwardly and an upstanding handle formed on the upper edge of said body consisting of a rectangular plate hav-

ing an elongated opening therein and longitudinal beads on the edges thereof.

In testimony whereof I affix my signature in presence of two witnesses.

WILLIAM R. PARARO.
